SAFETY GATE

James D. Jordan, Washington, D. C., assignor to
the United States of America as represented by
the Secretary of the Navy

Application May 1, 1943, Serial No. 485,408

2 Claims. (Cl. 102—79)

1

This invention relates to a safety device which is designed to be inserted in a rotatable explosive projectile, particularly between a squib and a booster charge located within the projectile.

An object of the invention is to prevent premature detonation of a projectile.

Another object of the invention is to provide a safety device which has relatively few operating parts, is simple in construction and may be easily assembled from parts manufactured by mass production.

More specifically, an object of the invention is to provide a safety gate which, before the projectile has been fired from a gun, will prevent an explosive charge of a squib, if prematurely detonated, from igniting an explosive charge of a booster.

Another specific object of the invention is to provide a locking or holding means for preventing a safety gate from being actuated from a safe position to armed position until the locking means has been rendered ineffective by the action of centrifugal force created by the rapid rotation of the projectile.

Still further objects of the invention, not specifically mentioned above, will become evident during the course of the following description.

In the drawings:

Fig. 1 is a perspective view, partly in section, of a device embodying the invention;

Fig. 2 is a sectional view taken on plane 2—2 of Fig. 1, showing the parts in safe position;

Fig. 3 is a sectional view taken on plane 2—2 of Fig. 1 but showing the parts in armed position; and,

Fig. 4 is a vertical sectional view taken on plane 4—4 of Fig. 2, showing the device mounted in a customary booster adapter, the adapter being shown in section in addition to the structure shown in Fig. 2.

In the drawings, similar reference numerals are used to indicate like parts throughout the views.

Numerical 10 generally indicates the body of the gate, which is preferably in the form of a short, disk-like cylinder, as shown in perspective in Fig. 1. The body 10 is formed with a cut-out portion or recess 11 which is substantially rectangular in shape and extends transversely of the body 10. It will be noted that the recess 11 terminates short of the axis of the body, but is provided with a restricted continuation 12 that extends beyond the axis of the body. In this connection, it will be understood, of course, that the axis of the body 10 is disposed coaxially with respect to the booster adapter 14 and to a discharge port 13 located in

2

the upper portion of the adapter. The adapter 14 is designed to be mounted within a projectile or the like (not shown). See Figure 4.

A gate element generally indicated at 15 is slidably mounted within the recess 11, the gate element 15 being provided with an enlarged portion 16 and a reduced tongue portion 17, the tongue portion 17 fitting within the recess continuation 12. The tongue 17 provides a shoulder 18, which is designed to abut the shoulder 19 formed by the continuation 12 of the recess 11. The gate 15 is provided with a vertical port 20, and it should be noted at this point that the gate 15 is designed to overlie and close off the port 13 in the adapter 14 when the gate 15 is in its innermost position as shown in Fig. 2. Also, the port 20 formed in the gate 15 will be aligned with the port 13 when the gate 15 is in its outermost position as shown in Fig. 3, thus providing direct communication through the gate and said port.

It will be noted that the gate element 15, inclusive of its tongue portion 17, is of rectangular cross section as may be seen in Fig. 4, where the shapes of portions 16 and 17 are shown clearly.

25 This rectangular shape affords several distinct advantages. Obviously, a gate of non-circular cross section cannot rotate about any longitudinal axis and therefore the ports 20 and 13 cannot turn out of the requisite relationship to assure registration of said ports at the proper time; the gate may be made relatively thin while maintaining sufficient strength in spite of the port 20 therein; and the wide portion 16 affords increased centrifugal force.

35 The body 10 is provided with diametrically opposed slots 21 and 22 formed in the periphery thereof, the slots forming flat inner walls 23, as best seen in Fig. 3. Cylinders or bores 24 and 25 are positioned within the body 10 and weighted detents 26 and 27 are positioned within the cylinders 24 and 25 respectively. These detents 26 and 27 are provided with pins 28 on their innermost ends. The tongue portion 17 of the gate 15 is provided with sockets 29, into which the pins 28 are designed to fit. Flat springs 30 are positioned within the slots 21 and 22 and are designed to lie against the flat side walls 23 as best seen in Fig. 2. These flat springs 30 urge the detents 26 and 27 into their innermost positions, thus keeping the pins 28 in locking engagement with the tongue 17 through cooperation with sockets 29. A suitable retaining ring 31 (see Fig. 1) is slipped around the periphery of the body 10 to retain the springs 30 within the slots 21 and 22. 50 A suitable cover plate 32 (see Fig. 4) is positioned

over the outer face of the body 10 and is held in its position by the adapter 14. This cover plate 32 is provided for preventing the gate 15 from being displaced from within the recess 11. The bottom wall of the booster adapter 14 will, of course, prevent the gate 15 from being displaced downwardly. As shown in Fig. 4, the gate 15 is of a thickness slightly less than that of the body so that the gate 15 may slide freely in the recess 11.

In operation, the safety device will be mounted within an adapter for a booster charge, and will be positioned between the booster charge and a squib. The gate 15 is locked in its innermost position as shown in Fig. 2, thus preventing communication between the squib and the booster charge. After the projectile has been fired from a gun and the initial setback force overcome, the centrifugal force created by the rotation of the projectile will throw the weighted detents 26 and 27 outwardly against the tension of the springs 28, thus causing disengagement between the pins 29 and sockets 29. After the detents are forced outwardly, thereby unlocking the gate 15, the gate 15 will also be forced outwardly by centrifugal force and the port will assume the position shown in Fig. 3. In this position, the device is in armed condition, and the port 20 formed in the tongue 17 of gate 15 will be aligned with the port 13 formed in the booster adapter, thereby providing direct communication from a squib (not shown), through the safety device, to a booster charge.

Obviously, many modifications and variations of the present invention are possible in the light of the above teachings. It is therefore to be understood that within the scope of the appended claims the invention may be practiced otherwise than as specifically described.

What is claimed is:

1. In a centrifugally operated safety device for projectiles having a controlled port in a fuse train, the combination with a body member having a transverse, substantially diametrically located, parallel-sided recess open to the port, and spaced lateral slots at opposite sides of the recess, of a slide gate guided in said recess and of rectangular cross section, and having a port initially closed to the first port, said body member having a pair of transversely directed bores, 45 opposed radially retractable detents slidably

5 mounted in said bores engaging said gate and flat spring blades mounted in said slots, each blade being of the same width as the slot in which it is located, and normally lying flat against the bottom of said slot, for resiliently retaining said detents.

2. In a centrifugally operated safety device for projectiles having a controlled port in a fuse train, the combination with a body member having a transverse, substantially diametrically located, parallel-sided recess and a reduced extension thereof open to said port and forming spaced stop shoulders, said body member also having diametrically opposed slots in its edge, the bottom surfaces of said slots being parallel to the sides of the recess, of a slide gate having a relatively massive outer end portion fitting in and guided in said recess and having a reduced tongue located in said extension and in engagement with said shoulders, said gate being of rectangular cross section, whereby rotation of the gate about any longitudinal axis is prevented, said body member having a pair of opposed transversely directed guide bores extending through the bottom surfaces of the slots and opening into the reduced extension of the recess, a pair of transversely opposed detents housed movably in said bores and having retaining means engaging said tongue, and flat spring blades mounted in the slots and normally each lying flat against the bottom of its respective slot, for resiliently holding the detents in tongue-engaging position.
